UNITED STATES PATENT OFFICE.

BERT L. VAN ORMAN, OF DETROIT, MICHIGAN, ASSIGNOR TO L. A. YOUNG INDUSTRIES, INC., OF DETROIT, MICHIGAN.

WIREWORKING MACHINE.

Application filed March 13, 1924. Serial No. 698,873.

To all whom it may concern:

Be it known that I, BERT L. VAN ORMAN, a citizen of the United States, residing at Detroit, county of Wayne, State of Michigan, have invented certain new and useful Improvements in Wireworking Machines, of which the following is a specification.

This invention relates to improvements in wire working machines.

In the use of coiled tension springs, it is necessary that means be provided for fastening the ends of the spring to the machine parts which are to be actuated by the spring. A common method is to form a suitable eye or hook at each end from a portion of the spring wire which must be provided for in coiling the spring by leaving uncoiled stock which is a disadvantage in the coiling operations or the spring must be partially uncoiled.

This invention relates to a machine for uncoiling or straightening a portion of the coils of a coiled spring. One of the main objects being to provide a machine capable of accomplishing this result with a minimum amount of manual assistance.

A second object is to provide means of readily adjusting the machine to springs of different size, and for straightening different lengths of wire.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which:

Fig. I, Sheet 1, is a fragmentary view in perspective of a machine embodying the features of my invention.

Fig. II, Sheet 2, is a partial plan view thereof.

Fig. III, Sheet 3, is a fragmentary view in elevation taken from the front of Fig. II.

Fig. IV, Sheet 4, is an enlarged detail view in section on a line corresponding to line 4—4 of Fig. II.

Fig. V, Sheet 5, is an enlarged fragmentary detail view in section on a line corresponding to line 5—5 of Fig. III.

Fig. VI, Sheet 6, is an enlarged detail

view in section on a line corresponding to line 6—6 of Fig. III.

Fig. VII, Sheet 2, is an enlarged fragmentary view in section on a line corresponding to line 7—7 of Fig. II, illustrating details of a spring turntable or conveyor.

Fig. VIII, Sheet 6, is an enlarged detail view in section on a line corresponding to line 8—8 of Fig. VI, illustrating details of a spring turntable or conveyor actuating lever.

Fig. IX, Sheet 6, is an enlarged detail view in section on a line corresponding to line 9—9 of Fig. VI, showing further spring turntable or conveyor details.

Fig. X, Sheet 6, is a detail view in section on a line corresponding to line 10—10 of Fig. IX.

Fig. XI, Sheet 3, is an enlarged view in section on a line corresponding to line 11—11 of Fig. V, illustrating details of a spring conveyor brake.

Fig. XII, Sheet 7, is an enlarged detail view in section on a line corresponding to line 12—12 of Fig. V, showing the wire pulling mechanism engaging the lower coil of a spring.

Fig. XIII, Sheet 7, is a detail view in elevation of a spring holder pin with a coil spring in elevated position thereon.

Fig. XIV, Sheet 3, is a detail enlarged view in section on a line corresponding to line 14—14 of Fig. III, illustrating details of a spring retainer.

Fig. XV, Sheet 3, is a detail view in section on a line corresponding to line 15—15 of Fig. III, showing further spring retainer details.

Fig. XVI, Sheet 4, is a detail view in section on a line corresponding to line 16—16 of Fig. IV, illustrating details of the wire puller slide.

Fig. XVII, Sheet 4, is a detail view in section on a line corresponding to line 17—17 of Fig. IV, illustrating details of a wire puller slide brake.

Fig. XVIII, Sheet 4, is a detail view in section on a line corresponding to line 18—18 of Fig. IV, illustrating details of a wire puller control member.

Fig. XIX, Sheet 6, is an enlarged detail view in section on a line corresponding to line 19—19 of Fig. II, illustrating wire puller driving and control details.

Fig. XX, Sheet 7, is a view similar to

Fig. XII, showing the parts in actuated position.

Fig. XXI, Sheet 2, is a view in section on a line corresponding to line 21—21 of Fig. XX, showing further details of the wire puller or straightener.

Fig. XXII, Sheet 4, is a view in section on a line corresponding to line 22—22 of Fig. VI, illustrating details of an adjustable cam member.

Fig. XXIII, Sheet 5, is an enlarged view in section on a line corresponding to line 23—23 of Fig. V, showing details of wire cut-off mechanism.

In the drawing, similar reference characters refer to similar parts throughout the several views, the sectional views being taken looking in the direction indicated by the little arrows at the ends of the section lines.

The machine is driven by any suitable means as the belt 24 and pulley 25, the latter being carried by a shaft 25' which also carries a worm 26 engaging a worm wheel 27—see Figs. I, II, III and IV. The worm wheel 27 is secured to a vertical shaft 28 which imparts motion to various mechanisms of the machine—see Fig. IV.

The work, the coiled spring 30, is successively moved to the different positions for the several operations by a turntable or conveyor 31 rotatable on a post 32 which is secured to the main frame 33—see Figs. I, II, III and V. The turntable is intermittently rotated by a ratchet lever 34 which is pivoted on the post 32 and which carries a pawl 35 engaging teeth 36 in an annular rack 29 on the under side of the turntable—see Figs. VII to X inclusive.

As a preferred form of construction, the pawl 35 is contained in a recess 37 and yieldingly supported by a spring 38, the shank 35' of the pawl being squared to prevent the pawl from rotating out of correct position—see Figs. IX and X. The ratchet lever 34 is connected by an adjustable link 39 to a cam lever 40 which is pivoted at 41 and engaged by a cam 42 on the shaft 28. The lever 40 is held in contact with the cam 42 by a spring 43 which is supported by a reciprocatable spring keeper 44—see Figs. III and IV.

The turntable 31 is advanced one step with each revolution of the shaft 28 and between movements is held in correct position by a pivoted locking dog or detent 45 which successively engages notches 46 in a flange 47 of the table 31—see Figs. III and VII. The detent is pivoted at 48 and connected by an adjustable link 49 to a bell crank 50 which carries a roller 51 engaged by a cam 52 on the shaft 28—see Fig. IV. The roller is yieldingly held in contact with the cam by a spring 53 bearing against one

end of the detent 45. A brake 54 bearing 65 against the lower surface of the turntable offers sufficient resistance to movement of the table to prevent its overrunning the desired position—see Figs. III and V. This brake is yieldingly held in contact with the table 31 by a spring 55 contained in the cylindrical upright supporting member 56—see Fig. XI.

The turntable 31 carries a series of equally spaced spring holder pins 57. The operator places a coiled spring 30 upon one of the pins when the latter is in the position 57^b—see Fig. V. The next movement of the turntable carries the spring to the position 57^b. A wire gripper 59 now advances toward the spring 30 and the hooked pivoted jaw 60 of the gripper passes underneath the lower coil of the spring—see Fig. XII. Each of the pins 57 has a longitudinal groove 61 registering with a notch 62 in the periphery of the work table or conveyor 31 to provide clearance for entrance of the jaw 60. As a preferred means of securing the work holding pins 57 to the table, each pin terminates in an offset screw threaded extension 63 on 80 which is threaded a nut 64, the latter having a spool or spacer portion 65 to allow clearance for the jaw 60. A segmental flange 66 on the pin provides a seat on which the spring 30 rests—see Fig. XIV, the end 95 of the flange providing a stop 67—see Fig. XIII—against which the end 68 of the bottom coil of the spring is placed by the operator to insure correct positioning of the spring on the pin and engagement of the 100 jaws of the gripper 59 at the correct point of the bottom spring coil.

When in position 57^b, the spring 30 is yieldingly retained in place on the pin 57 by a plate 70 under which the spring 30 105 passes as it moves to this position—see Figs. I, III and XIV. The plate 70 is supported by an arm 71 on a standard 72 which is vertically adjustable in the sleeve-like bracket 73 to change the height of the plate 70 for springs of different lengths—see Fig. XV. The plate 70 is hinged to a bracket 74 on the arm 71 and urged downward by a spring 75, an adjustable stop 76 supporting the plate 70 when the latter is not in engagement with 110 one of the springs 30. As the jaw 60 passes underneath the spring 30, the latter is lifted slightly from its seat on the pin 57, the plate 70 yielding to allow the spring to rise. When the gripper 59 has reached its work 120 engaging position, the plate 70 reseats the spring 30 on the pin 57 thereby placing the lower coil 77 of the spring in range of the hook 78 on the jaw 60—see Fig. XII.

The gripper 59 is mounted on a carriage 80 reciprocable in the channel ways 81 of the longitudinal guide members 82—see

Figs. IV and XVI. The gripper carriage 80 is actuated with an intermittent movement which I will now describe.

A draw bar 83 is disposed longitudinally 5 of the carriage and has a lost motion connection thereto, the carriage having slots 85 therein engaged by the bolts 84 thus permitting a limited relative movement between these parts or a lost motion connection. The 10 actuating or driving member is connected to this bar 83 by a combined friction and positive driving means, as will be described.

The carriage is provided with a brake or 15 friction means to insure this lost motion action. A brake 86 is mounted upon the bracket 87 carried by the carriage, the brake coacting with a stationary arm 88 disposed between the brake shoes 89 and 90 on the bracket 87. The desired amount of friction 20 is provided by compression springs 91 carried by the spring keepers 92 having adjusting nuts 93—see Figs. IV and XVII. The actuating member 95 is reciprocatingly mounted on the guide ways 82, the member 25 95 being connected to the crank pin 97 on the cam 88 by means of the adjusting link or pitman 98—see Figs. IV and VI.

For convenience in assembling and to 30 compensate for wear the ways 82 are adjustably supported by means of the adjusting screws 94 and the clamping screws 96 engaging elongated bolt holes 82—see Fig. XVI.

The driving connection from the actuating 35 member 95 to the carriage draw bar 83 whereby the constant movement of the actuating member is changed into an intermittent movement for the carriage comprises a combined friction and positive driving or connecting clutch 100. This clutch 40 consists of a bar 99 on the actuating member, a friction shoe 101 rigidly secured to the bar 83 and underlying the bar 99 actuating the cross head and an upper shoe 102 which is 45 vertically reciprocable on bolts 103 in the shoe 101 and yieldingly held against the top surface of the bar 99 by the springs 104, means being provided for regulating the tension of these springs.

The shoes 101 and 102 are provided with 50 facings 105 of friction material which grip the bar 99 with sufficient friction to cause the carriage 83 to advance with the actuating member until the shoe 101 engages the stop 106—see Figs. II and XIX. The stop 55 106 is moved into and out of range of the shoe 101 by means of a cam lever 107 actuated by a cam 108 on the shaft 28,—see Fig. XIX. The roller 109 on the lever 107 60 is held yieldingly against the cam 98 by a spring 110. To prevent breakage of the parts the lever 107 is yieldingly held in engagement with its pivot 111 by the spring 112, the lever being provided with a notch-like opening 113 engaging the pivot 111,

thereby permitting the lever to swing away from its pivot in case the clutch 100 should become displaced or the parts should not be operated in proper order, thereby interrupting the normal movement of the stop 70 106—see Figs. II and XIX.

After the clutch shoe has engaged the stop 106 the actuating member 95 continues to advance the bar sliding through the control member until the clutch pawl 115 drops 75 into the hole 116 in the bar 99. The actuation of the parts is timed so that at this instant the stop 106 is retracted allowing the carriage 83 to advance with the actuating member by which it is now positively 80 driven. These parts continue to advance together until the gripper is in position to engage the lower coil of the spring 30.

The adjustment of the connecting rod 98 provides means for accurately determining 85 this position and means for changing the position for springs of different diameters.

The movable jaw 60 of the gripper is pivoted at 117—see Fig. XII, to the levers 118 on the gripper 59, this gripper having 90 a fixed jaw 119 adapted to coact with the pivoted jaw 60. In addition to its supporting pivot 117 the jaw 60 is yieldingly suspended by a line 120 carried by the blade spring 121. The lower ends of the levers 95 118 are connected by a link 122 to the bar 83.

When the actuating member 95 advances on its forward stroke the bar 83 owing to the lost motion connection to the carriage as described, swings the lever 118 forwardly 100 opening the jaw 60. The carriage is then moved forwardly with the bar 83, the jaw being held open until the end of the forward stroke is reached—see Figs. IV and XII. On the return stroke of the actuating 105 member 95 the carriage is moved backwardly with the bar 83, the lever 118 being held open until the end of the return stroke is reached—see Figs. IV and XII. The carriage is then actuated.

As the gripper 59 moves away from the spring holder 57 with the wire 69 in its grasp the spring is uncoiled, the uncoiled portion being pulled away from the spring, 115 as shown in Figs. XX and XXI. As the wire is pulled out or the spring uncoiled the wire is drawn against the straightening pin 123 which removes the bends or straightens the wire, leaving the extended or pulled out portion straight with the exception of the hooked end portion 124 held by the gripper jaws.

The pin 123 is supported by a rod 125 which is longitudinally adjustable in the 125 brackets 126 so that the position of the straightening pin may be adjusted for springs of different diameters—see Figs. V and VI. The length or amount of wire pulled from the coil is determined by the 130

position of the shoulder-like stops 128 on the stop rod 129. This stop rod is adjustably supported in the bracket 130—see Figs. II and IV. The gripper 59 continues to travel away from the spring holders 57 until the clutch 100 contacts with the shoulders 128, the front end 131 being disposed through openings 132 and 133 in the shoe 102 and the pawl 115 respectively—see Fig. IV.

At substantially the same time that the member 101 contacts or comes to rest against the stops 128, the pawl 115 is lifted by the cam portion 135 of the stop rod leaving only the frictional clutch connection for the actuating member and the carriage so that the actuating member may complete its stroke without further movement of the carriage and the jaw is opened to release the work. This also permits utilization of more or less of the stroke of the actuating member as may be required for the particular work.

The wire is removed from the gripper by an ejector 136 carried by the rocker arm 137 pivoted at 138—see Figs. II, V, VI and XII. This rocker arm is actuated by the cam arm 139 on the vertical shaft 140—see Figs. XII and XIX. The shaft 140 is provided with an arm 141 connected by the adjustable link 142 to a bell crank lever 143 which is in turn connected to the rocker arm 137 by the adjustable link 144. The ejector is returned to its initial position by the spring 145. The cam arm 139 lies in the path of a cam member 146 carried by the cams 42 and 52, see Figs. IV, V and VI.

In the structure illustrated the cam 146 is pivotally mounted on a pin 147 which extends through the cams 42 and 52, see Fig. XXII. The pin provides means by which the cams 42 and 108 are driven from the cam 52, the latter only being directly secured to the shaft 28. The cam 146 may be turned on the pin 147 and held in its adjusted position by means of the screw 148, this adjustment providing means for changing the amount of movement of the ejector 136. The ejector is shown in its actuated position by dotted lines in Fig. XXI.

After the wire has been released or ejected from the gripper the work table carries another spring into the position 57^b and carries the partially uncoiled spring to the position 57^c where the hook or unstraightened end portion 124 is cut off. As the spring is carried from the position 57^b the extending end 69 is drawn around the straightening pin 123 and swung back to the position shown in Fig. II. The spring next comes in contact with the end 149 of a positioning lever 150 which is pivoted at 151 and yieldingly held against the stop pin 152 by a spring 153. The bracket 154 which carries the lever 150 is secured to the standard 155

by the screw 156. By loosening the screw the bracket may be rotated as desired to adjust the position of the lever relative to the work table.

As the spring is carried forward to position 57^c the end of the lever 149 is pushed ahead, the other end 157 of the lever is swung around to the position shown by dotted lines in Fig. V carrying the extending or uncoiled end of the spring around with it. When the work has passed the end 149 of the lever, the spring 153 returns the lever to its initial position. After passing the positioning lever 150 the work 30 engages the face of a spring rotating shoe 80 158 pivoted on the bracket 154 at 159 and yieldingly held toward the table by the spring 160, see Fig. V.

The shoe 158 has a facing 161 of frictional material with which the spring engages 85 causing the spring to rotate on its supporting pin, thereby swinging the extended end thereof into operative relation to the cut-off mechanism 162. The stop 163 supports the member 158 in its initial position, see Fig. II. 90

The cut-off mechanism 162 consists of a bracket member 165 carrying the shear block 166. A cutter 167 is pivoted to the bracket 165 and carries the adjustable plate 168. The plate 168 is adjustably secured to the cutter by means of the set screw 170 and the adjusting screw 169, see Figs. I and XXIII. The spring rotating shoe 158 swings the projecting or extended end 69 of the spring over the shear block and underneath the cutter. The cutter is actuated by the lever 172 on the cam 108, see Fig. V, the cam lever engaging the roller 173 of a lever 174 on the rock shaft 175. The rock shaft has an arm 176 connected by the adjustable link 177 to the cutter.

When the cutter is actuated by the mechanism described the blade moves downwardly across the face of the shear block thereby cutting off the hooked or unstraightened portion of the spring. The roller 173 is held in contact with the cam 108 by means of the springs 187. The supporting bracket for the cutter is slidably supported in the dove-tailed way 180 in the main frame 33 providing means for adjusting the position of the cut-off for leaving any desired length of wire extending from the spring, the bracket being secured in its adjusted position by means of the set screw 181. The arm 176 is splined to the rock-shaft 175 so that it may be moved longitudinally thereon to aline with the adjustment of the cutter.

After the wire has been cut off the work 125 is then carried to the position 57^d where it is engaged by the spring ejector. A satisfactory type of ejector consists of the rotating brush 183 which is driven at a speed sufficient to lift the spring from the pin 130

throwing it against the deflector 184, see Figs. I, II and III. This deflector is adjustably supported on a bracket 185 and guides the spring to its receptacle.

5 In the embodiment illustrated the ejector brush is driven by a belt 186 connecting the pulley 187 on the shaft 188 of the brush with the main pulley 25. The empty holder is carried by the next actuation of the work 10 table to the position 57^a, having finished a complete cycle of movement of the work table. The several operations, placing the spring upon a holder, uncoiling, cutting off and ejecting, are carried on simultaneously 15 on different springs. All of the mechanisms except the ejector 183 are driven by the shaft 28 so that the different parts are correctly timed and their timed relation is easily maintained.

20 I have illustrated and described an embodiment of my invention which I have found very satisfactory. I have not attempted to illustrate or describe certain modifications and adaptations which I 25 contemplate as I believe the disclosure made will enable those skilled in the art to embody or adapt my improvements as may be desired.

Having thus described my invention what 30 I claim as new and desire to secure by Letters Patent is:

1. In a structure of the class described, the combination of a work holder, a reciprocatingly mounted carriage provided with a 35 fixed jaw and a pivoted jaw, a brake for frictionally retarding the movement of said carriage, means for actuating said carriage and said jaw comprising a draw bar having a lost motion connection to said carriage and operatively connected to said pivoted jaw so 40 that the jaw is opened and closed by the independent movement of said draw bar at the ends of the stroke of the carriage, a reciprocating actuating member, a driving connection 45 for said actuating member and draw bar comprising a clutch bar on said driving member having a hole therein, a friction shoe on said draw bar coacting with said clutch bar providing a friction drive connection, a driving pawl 50 on said draw bar adapted to engage said hole in said clutch bar providing a positive drive connection, a stop for holding said carriage on its forward stroke to permit engagement of said pawl, means for retracting said stop timed with the engagement of said driving 55 pawl, a cam for disengaging said driving pawl on the return stroke of the carriage, and an adjustable return stop for said carriage positioned to engage after said pawl has been 60 disengaged.

2. In a structure of the class described, the combination of a work holder, a reciprocatingly mounted carriage provided with a fixed jaw and a pivoted jaw, means for actuating said carriage and said jaw comprising

ing a draw bar having a lost motion connection to said carriage and operatively connected to said pivoted jaw so that the jaw is opened and closed by the independent movement of said draw bar at the ends of the 70 stroke of the carriage, a reciprocating actuating member, a driving connection for said actuating member and draw bar comprising a clutch bar on said driving member having a hole therein, a friction shoe on said draw bar coacting with said clutch bar providing a friction drive connection, a driving pawl on said draw bar adapted to engage said hole in said clutch bar providing a positive drive connection, a stop for holding said 75 carriage on its forward stroke to permit engagement of said pawl, means for retracting said stop timed with the engagement of said driving pawl, a cam for disengaging said driving pawl on the return stroke of the carriage, and an adjustable return stop for said carriage positioned to engage after said pawl has been 80 disengaged.

3. In a structure of the class described, the combination of a work holder, a reciprocatingly mounted carriage provided with a work engaging jaw, a brake for frictionally retarding the movement of said carriage, means for actuating said carriage and jaw comprising a carriage draw bar having a 90 lost motion connection to said carriage and an operative connection to said jaw, a reciprocating actuating member, a combined friction and driving connection for said actuating member and draw bar comprising a clutch bar on said driving member having a hole therein, a friction shoe on said draw bar coacting with said clutch bar providing a friction drive connection, a driving pawl on said draw bar adapted to engage said hole 95 in said clutch bar providing a positive drive connection, a stop for holding said carriage on its forward stroke to permit engagement of said pawl, means for retracting said stop timed with the engagement of said driving 100 pawl, a cam for disengaging said driving pawl on the return stroke of the carriage, and a return stop for said carriage positioned to engage after said pawl has been 105 disengaged.

4. In a structure of the class described, the combination of a work holder, a reciprocatingly mounted carriage provided with a work engaging jaw, means for actuating said carriage and said jaw comprising a carriage draw bar having a lost motion connection to said carriage and an operative connection to said jaw, a reciprocating actuating member, a combined friction and driving connection for said actuating member and draw bar comprising a clutch bar on said driving member having a hole therein, a friction shoe on said draw bar coacting with said clutch bar providing a friction 120 drive connection, a driving pawl on said 125 draw bar

draw bar adapted to engage said hole in said clutch bar providing a positive drive connection, a stop for holding said carriage on its forward stroke to permit engagement 5 of said pawl, means for retracting said stop timed with the engagement of said driving pawl, and a cam for disengaging said driving pawl on the return stroke of the carriage.

10 5. In a structure of the class described, the combination of a work holder, a reciprocatingly mounted carriage provided with a fixed jaw and a movable jaw, a brake for frictionally retarding the movement of said carriage, means for actuating said carriage and said jaw comprising a draw bar having a lost motion connection to said carriage and operatively connected to said pivoted jaw so that the jaw is opened and closed by the independent movement of said draw bar at the 20 ends of the stroke of the carriage, a reciprocating actuating member, a driving connection for said actuating member and draw bar comprising a friction shoe providing a friction drive and a pawl providing when engaged a positive drive, means for temporarily holding said carriage on its forward stroke to permit engagement of said pawl, means for disengaging said pawl during the 25 return stroke of the carriage, and a carriage return stop positioned to engage after said pawl has been disengaged.

30 6. In a structure of the class described, the combination of a work holder, a reciprocatingly mounted carriage provided with a fixed jaw and a movable jaw, means for actuating said carriage and said jaw comprising a draw bar having a lost motion connection to said carriage and operatively connected to said pivoted jaw so that the jaw is opened and closed by the independent movement of said draw bar at the ends of the 35 stroke of the carriage, a reciprocating actuating member, a driving connection for said actuating member and draw bar comprising a friction shoe providing a friction drive and a pawl providing when engaged a positive drive, means for temporarily holding said carriage on its forward stroke to permit engagement of said pawl, and means for disengaging said pawl during the return stroke of the carriage.

40 7. In a structure of the class described, the combination of a work holder, a reciprocatingly mounted carriage provided with a fixed jaw and a movable jaw, means for frictionally retarding the movement of said carriage, and means for actuating said carriage and said jaw comprising a draw bar having a lost motion connection to said carriage and operatively connected to said pivoted jaw so that the jaw is opened and closed by the independent movement of said draw bar at the ends of the stroke of the carriage.

45 8. In a structure of the class described,

the combination of a work holder, a reciprocatingly mounted carriage provided with a work engaging jaw, a brake for frictionally retarding said carriage, means for actuating said carriage and jaw comprising a carriage draw bar having a lost motion connection to said carriage and an operative connection to said jaw whereby the jaw is opened and closed by the movement of said draw bar independent of the carriage, a combined friction and positive driving connection for said actuating member to said draw bar comprising a friction shoe and a pawl means for temporarily holding said carriage on its forward stroke to permit the engagement of said pawl, means for disengaging said pawl during the return stroke of the carriage, and a carriage return stop positioned to engage after the pawl has been disengaged.

50 9. In a structure of the class described, the combination of a work holder, a reciprocatingly mounted carriage provided with a work engaging jaw, means for actuating said carriage and jaw comprising a carriage draw bar having a lost motion connection to said carriage and an operative connection to said jaw whereby the jaw is opened and closed by the movement of said draw bar independent of the carriage, a combined friction and positive driving connection for said actuating member to said draw bar comprising a friction shoe and a pawl means for temporarily holding said carriage on its forward stroke to permit the engagement of said pawl, and means for disengaging said pawl during the return stroke of the carriage.

55 10. In a structure of the class described, the combination of a work holder, a reciprocatingly mounted carriage provided with work engaging jaws, means for frictionally retarding the movement of said carriage, means for actuating said carriage including a friction and a positive driving means, and means for controlling said positive driving means whereby it is engaged and disengaged at a point intermediate the stroke of the carriage, said driving means having a lost motion connection to said carriage and being operatively connected to said jaw whereby the jaws are actuated to engage and release the work.

60 11. In a structure of the class described, the combination of a work holder, a reciprocatingly mounted carriage provided with work engaging jaws, means for actuating said carriage including a friction and a positive driving means, and means for controlling said positive driving means whereby it is engaged and disengaged at a point intermediate the stroke of the carriage.

65 12. In a structure of the class described, the combination of a work table provided with a pin-like upright work holder adapted

- to receive a coiled spring, said work holder being provided with a stop shoulder adapted to coact with the end of the bottom coil of a spring, said table and work holder being 5 notched to permit the entrance of a work engaging jaw below the bottom coil of the spring, a reciprocating carriage provided with a forwardly facing fixed jaw, a coacting upwardly facing hooked jaw, means for 10 adjustably supporting said hooked jaw comprising a lever pivotally mounted on said carriage and having said hooked jaw pivotally mounted thereon, a link engaging said hooked jaw in front of its pivot, a supporting 15 spring for said link, and a jaw actuating member having a lost motion connection to said carriage and a link connection to said lever.
13. In a structure of the class described, 20 the combination of a work holder adapted to receive a coiled spring, a reciprocating carriage provided with a forwardly facing fixed jaw, a coacting upwardly facing hooked jaw, means for supporting said 25 hooked jaw comprising a lever pivotally mounted on said carriage and having said hooked jaw pivotally mounted thereon, a link engaging said hooked jaw in front of its pivot, a supporting spring for said link, and a jaw actuating member having a lost motion connection to said carriage and a link connection to said lever.
14. In a structure of the class described, 30 the combination of a pin-like work holder adapted to receive a coiled spring and provided with a work positioning stop with which the end of the bottom coil of the spring may be engaged, a reciprocating carriage provided with work engaging jaws 35 adapted to engage the bottom coil of the spring adjacent its end, means for reciprocating said carriage and automatically opening and closing said jaws to engage and release the work, a straightening pin disposed in 40 spaced relation to said work holder and so that the wire is drawn against the same as it is uncoiled, and means for lifting the work from the jaws arranged to engage the uncoiled end thereof.
15. In a structure of the class described, 45 the combination of a pin-like work holder adapted to receive a coiled spring and provided with a work positioning stop with which the end of the bottom coil of the spring may be engaged, a reciprocating carriage provided with work engaging jaws adapted to engage the bottom coil of the spring adjacent its end, means for reciprocating said carriage and automatically opening and closing said jaws to engage and release the work, and a straightening pin disposed in 50 spaced relation to said work holder and so that the wire is drawn against the same as it is uncoiled.
16. In a structure of the class described, 55 the combination of a pin-like work holder adapted to receive a coiled spring and provided with a work positioning stop with which the end of the bottom coil of the spring may be engaged, a reciprocating carriage provided with work engaging jaws adapted to engage the bottom coil of the spring adjacent its end, means for reciprocating said carriage and automatically opening and closing said jaws to engage and release the work, and a straightening pin disposed in 60 spaced relation to said work holder and so that the wire is drawn against the same as it is uncoiled.
17. In a structure of the class described, 65 the combination of a pin-like work holder adapted to receive a coiled spring and provided with a work positioning stop with which the end of the bottom coil of the spring may be engaged, a reciprocating carriage provided with work engaging jaws adapted to engage the bottom coil of the spring adjacent its end, means for reciprocating said carriage and automatically opening and closing said jaws to engage and release the work, and means for lifting the work from the jaws arranged to engage the uncoiled end thereof.
18. In a structure of the class described, 70 the combination of a pin-like work holder adapted to receive a coiled spring and provided with a work positioning stop with which the end of the bottom coil of the spring may be engaged, a reciprocating carriage provided with work engaging jaws adapted to engage the bottom coil of the spring adjacent its end, and means for reciprocating said carriage and automatically opening and closing said jaws to engage and release the work.
19. In a structure of the class described, 75 the combination of a work holder adapted to rotatably support a coiled spring, a reciprocating carriage provided with work engaging jaws adapted to engage the bottom coil of the spring supported on said work holder, means for reciprocating said carriage and automatically opening and closing said jaws to engage and release the work, a straightening pin disposed in 80 spaced relation to said work holder and so that the wire is drawn against the same as it is uncoiled, and means for lifting the work from the jaws arranged to engage the uncoiled end thereof.
20. In a structure of the class described, 85 the combination of a work holder adapted to rotatably support a coiled spring, a reciprocating carriage provided with work engaging jaws adapted to engage the bottom coil of the spring supported on said work holder, means for reciprocating said carriage and automatically opening and closing said jaws to engage and release the work, and a straightening pin disposed in 90 spaced relation to said work holder and so that the wire is drawn against the same as it is uncoiled.
21. In a structure of the class described, 95 the combination of a work holder adapted to rotatably support a coiled spring, a reciprocating carriage provided with work engaging jaws adapted to engage the bottom coil of the spring supported on said work holder, means for reciprocating said carriage and automatically opening and closing said jaws to engage and release the work, and a straightening pin disposed in 100 spaced relation to said work holder and so that the wire is drawn against the same as it is uncoiled.
22. In a structure of the class described, 105 the combination of a work holder adapted to rotatably support a coiled spring, a reciprocating carriage provided with work engaging jaws adapted to engage the bottom coil of the spring supported on said work holder, means for reciprocating said carriage and automatically opening and closing said jaws to engage and release the work, and a straightening pin disposed in 110 spaced relation to said work holder and so that the wire is drawn against the same as it is uncoiled.
23. In a structure of the class described, 115 the combination of a work holder adapted to rotatably support a coiled spring, a reciprocating carriage provided with work engaging jaws adapted to engage the bottom coil of the spring supported on said work holder, means for reciprocating said carriage and automatically opening and closing said jaws to engage and release the work, and a straightening pin disposed in 120 spaced relation to said work holder and so that the wire is drawn against the same as it is uncoiled.
24. In a structure of the class described, 125 the combination of a work holder adapted to rotatably support a coiled spring, a reciprocating carriage provided with work engaging jaws adapted to engage the bottom coil of the spring supported on said work holder, means for reciprocating said carriage and automatically opening and closing said jaws to engage and release the work, and a straightening pin disposed in 130 spaced relation to said work holder and so that the wire is drawn against the same as it is uncoiled.

coiled, said straightening pin being adjustably supported.

21. In a structure of the class described, the combination of a work holder adapted to rotatably support a coiled spring, a reciprocating carriage provided with work engaging jaws adapted to engage the bottom coil of a spring supported on said work holder, and means for reciprocating said carriage and automatically opening and closing said jaws to engage and release the work.

22. In a structure of the class described, the combination of a rotatably mounted work table provided with a plurality of upright pin-like work holders adapted to receive coiled springs, means for actuating said table with a step by step movement, a gripper carriage reciprocating radially of said table and adapted to grip the bottom coil of a spring on said work holder, and a straightening pin across which the uncoiled wire is drawn on the retracting movement of the gripper carriage.

23. In a structure of the class described, the combination of a rotatably mounted work table provided with a plurality of upright pin-like work holders adapted to receive coiled springs, means for actuating said table with a step by step movement, and a gripper carriage reciprocating radially of said table and adapted to grip the bottom coil of a spring on said work holder.

24. In a structure of the class described, the combination of a rotatable work table, means for driving said table with a step by step movement, a plurality of uniformly spaced work holders mounted on said table and adapted to receive and support coiled springs in an upright position, a reciprocating gripper carriage adapted to engage the bottom coil of the spring whereby the spring is partially uncoiled on the retracting movement of the carriage, a yieldingly mounted plate adapted to engage the upper end of the spring when in operative relation to said carriage, and means for disengaging the work from the gripper adapted to lift the work against the said yielding plate.

25. In a structure of the class described, the combination of a rotatable work table, means for driving said table with a step by step movement, a plurality of uniformly spaced work holders mounted on said table and adapted to receive and support coiled springs in an upright position, a reciprocating gripper carriage adapted to engage the bottom coil of the spring whereby the spring is partially uncoiled on the retracting movement of the carriage, and a yieldingly mounted plate adapted to engage the upper end of the spring when in operative relation to said carriage.

26. In a structure of the class described, the combination of a rotatably mounted

work table provided with a plurality of upright pin-like work holders adapted to rotatably support coiled springs, a gripper carriage reciprocating radially of said table and adapted to grip the bottom coils of the springs, a straightening pin across which the uncoiled wire is drawn on the retracting movement of the gripper, an ejector for releasing the work from the gripper, a cutter, a work positioning lever adapted to engage the work as the table is rotated to swing the uncoiled end thereof inwardly, a work positioning shoe disposed at the rear of said lever to engage the work and rotate the same upon the work holders delivering the uncoiled ends thereof to the cutter, and means for actuating said table, gripper carriage and cutter in synchronism.

27. In a structure of the class described, the combination of a rotatably mounted work table provided with a plurality of upright pin-like work holders adapted to rotatably support coiled springs, a gripper carriage reciprocating radially of said table and adapted to grip the bottom coils of the springs, a cutter, a work positioning lever adapted to engage the work as the table is rotated to swing the uncoiled end thereof inwardly, a work positioning shoe disposed at the rear of said lever to engage the work and rotate the same upon the work holders delivering the uncoiled ends thereof to the cutter, and means for actuating said table, gripper carriage and cutter in synchronism.

28. In a structure of the class described, the combination of a rotatably mounted work table provided with a plurality of upright work holders adapted to rotatably support coiled springs, a gripper carriage reciprocating radially of said table and adapted to grip the bottom coils of the springs supported on said work holder, a cutter, a work positioning lever adapted to engage the work as the table is rotated to swing the uncoiled end thereof inwardly, a work positioning shoe disposed at the rear of said lever to engage the work and rotate the same upon the work holders delivering the uncoiled ends thereof to the cutter, and means for actuating said table, gripper carriage and cutter in synchronism.

29. In a structure of the class described, the combination of a rotatably mounted work table provided with a plurality of upright work holders adapted to rotatably support coiled springs, a gripper carriage reciprocating radially of said table and adapted to grip the bottom coils of the springs supported on said work holder, a cutter, a work positioning shoe disposed to engage the work and rotate the same upon the work holders delivering the uncoiled ends thereof to the cutter, and means for actuating said table, gripper carriage and cutter in synchronism.

30. In a structure of the class described, the combination of a rotatably mounted work table provided with a plurality of upright work holders adapted to rotatably support coiled springs, a reciprocating gripper carriage adapted to grip the bottom coils of the springs on said work holders, and a work positioning lever adapted to engage the work as the table is rotated to swing the uncoiled end thereof inwardly. 65
31. In a structure of the class described, the combination of a rotatably mounted work table provided with a plurality of upright pin-like work holders adapted to receive coiled springs, means for actuating said table with a step by step movement, a work gripper carriage reciprocating radially of said table and adapted to grip the bottom coils adjacent their ends, a straightening pin across which the uncoiled wire is drawn on the retracting movement of the gripper, an ejector for releasing the work from the gripper, a cutter, means for rotating the work upon the work holder as the table is rotated to swing the uncoiled end thereof into the cutter, and means for actuating said table, gripper carriage and cutter in synchronism. 70
32. In a structure of the class described, the combination of a rotatably mounted work table provided with a plurality of upright pin-like work holders adapted to receive coiled springs, means for actuating said table with a step by step movement, a work gripper carriage reciprocating radially of said table and adapted to grip the bottom coils adjacent their ends, a cutter, means for rotating the work upon the work holder as the table is rotated to swing the uncoiled end thereof into the cutter, and means for actuating said table, gripper carriage and cutter in synchronism. 75
33. In a structure of the class described, the combination of a rotatable work table, means for driving said table with a step by step movement, a plurality of uniformly spaced work holders mounted on said table and adapted to rotatably support coiled springs in an upright position, a reciprocating gripper carriage adapted to engage the bottom coils of the springs whereby they are partially uncoiled on the retracting movement of the carriage, a cutter, means actuated by the rotation of the table for positioning the work relative to said cutter, and means for actuating said cutter while the table is at rest. 80
34. In a structure of the class described, the combination of a rotatable work table, means for driving said table with a step by step movement, a plurality of work holders mounted on said table and adapted to rotatably support coiled springs in upright position, a reciprocating gripper carriage adapted to engage the bottom coils of the springs whereby they are partially uncoiled on the retracting movement of the carriage, a cutter, means for actuating said cutter, and means for actuating said table, carriage and cutter in synchronism. 85
35. In a structure of the class described, the combination of a rotatable work holder, means for driving said table with a step by step movement, a plurality of work holders mounted on said table and adapted to rotatably support coiled springs, a reciprocating gripper carriage adapted to engage end coils of the springs whereby they are partially uncoiled on the retracting movement of the carriage, and means for actuating said table and carriage in synchronism. 90
36. In a structure of the class described, the combination of a rotatable work table, means for driving said work table with a step by step movement, work holders mounted on said table and adapted to rotatably support coiled springs in an upright position, a reciprocating gripper carriage adapted to successively engage the bottom coils of the springs whereby they are partially uncoiled on the retracting movement of the carriage, a cutter, means actuated by the rotation of the table for positioning the uncoiled ends of the springs in operative relation to the cutter, and a rotating brush positioned to engage the springs when advanced from said cutter ejecting the same 95
37. In a structure of the class described, the combination of a rotatable work table, means for driving said work table with a step by step movement, work holders mounted on said table and adapted to rotatably support coiled springs, a reciprocating gripper carriage adapted to successively engage end coils of the springs whereby they are partially uncoiled on the retracting movement of the carriage, a cutter, and means actuated by the rotation of the table for positioning the uncoiled ends of the springs in operative relation to the cutter. 100
38. In a structure of the class described, the combination of a rotatable work table, means for driving said work table with a step by step movement, work holders mounted on said table and adapted to rotatably support coiled springs, a reciprocating gripper carriage having automatically acting gripping jaws adapted to successively engage end coils of the springs whereby they are partially uncoiled on the retracting movement of the carriage and means for actuating said table and carriage in synchronism. 105
39. In a structure of the class described, 110
40. In a structure of the class described, the combination of a rotatable work table, means for driving said work table with a step by step movement, work holders mounted on said table and adapted to rotatably support coiled springs, a reciprocating gripper carriage having automatically acting gripping jaws adapted to successively engage end coils of the springs whereby they are partially uncoiled on the retracting movement of the carriage and means for actuating said table and carriage in synchronism. 115
41. In a structure of the class described, the combination of a rotatable work table, means for driving said work table with a step by step movement, work holders mounted on said table and adapted to rotatably support coiled springs, a reciprocating gripper carriage having automatically acting gripping jaws adapted to successively engage end coils of the springs whereby they are partially uncoiled on the retracting movement of the carriage and means for actuating said table and carriage in synchronism. 120
42. In a structure of the class described, the combination of a rotatable work table, means for driving said work table with a step by step movement, work holders mounted on said table and adapted to rotatably support coiled springs, a reciprocating gripper carriage having automatically acting gripping jaws adapted to successively engage end coils of the springs whereby they are partially uncoiled on the retracting movement of the carriage and means for actuating said table and carriage in synchronism. 125

the combination of a work holder adapted to rotatably support coiled springs, a reciprocating carriage having automatically acting gripping jaws adapted to engage an end coil of a spring mounted on said holder on the forward movement of the carriage whereby the spring is partially uncoiled on

the retracting movement of the carriage, and means for automatically releasing said gripping jaws.

In witness whereof, I have hereunto set my hand.

BERT L. VAN ORMAN. [L.S.]
